UNITED STATES PATENT OFFICE.

MAX SCHMIDT, OF HAMBURG, GERMANY.

CLOCK FOR ADVERTISING PURPOSES.

Application filed April 16, 1921. Serial No. 461,936.

(GRANTED UNDER THE PROVISIONS OF THE ACT OF MARCH 3, 1921, 41 STAT. L., 1313.)

To all whom it may concern:

Be it known that I, MAX SCHMIDT, a citizen of the Republic of Germany, residing at Hamburg, Germany, have invented 5 certain new and useful Improvements in and Relating to Clocks for Advertising Purposes (for which I have filed applications in Germany, February 7, 1920; Netherlands, February 2, 1921; Switzerland, 10 February 3, 1921; Denmark, February 3, 1921; France, February 5, 1921; Great Britain, February 7, 1921; Sweden, February 2, 1921), of which the following is a specification.

15 It has already been proposed to use clocks for advertising purposes. In the clock according to this invention, by a suitable bending over of the shaft of the hand and by forming the projecting dial as an annulus 20 in its plane or behind the same, space is obtained in front of the hands for making the advertisement visible. The hands of the clock are so bent, that their ends lie above the dial and that they can each pass 25 the other properly. The space between the clock and the dial can be made of any depth according to the shape of the casing and the amount by which the dial projects. In the space an arrangement can be mounted, 30 which is driven in the ordinary manner and by which a change of advertisements is effected at different intervals.

The device is shown in the accompanying drawing in which—

35 Fig. 1 is a front elevation and Fig. 2 a section on the line A—B.

Fig. 1 shows how the clock appears to the observer. A clock is seen which has hands only at the edge of the dial, while the central part of the dial is filled in with the advertisement. The fact that the shaft of the hands cannot be seen enhances the effect of the advertisement. The constructional form is seen in Figure 2. In the casing 45 a the clock b is mounted in the usual manner. The shaft of the minute hand c

is bent over several times, while the end of the hand itself lies above the dial d. In a similar manner the hour hand e is bent over so that it will pass without catching between 50 the minute hand c on the one hand and the edge of the casing and the dial d on the other hand. Behind the annular dial is the advertisement f. According to the drawing between the advertisement, which is visible 55 from without, and the clock there is a considerable space, in which a roll-up advertisement is fitted.

Having now particularly described and ascertained the nature of my said invention 60 and in what manner the same is to be performed, I declare, that what I claim is:

An advertising clock, including a casing having an open end, a clock mounted therein, a dial having a central opening smaller than the opening in the casing mounted on the open end thereof, the dial closing a substantial portion of the opening in the casing, the clock having hands extending radially from the central axis formed with 70 forward laterally extending portions in close proximity to the wall of the casing, and U-shaped radially and inwardly projecting end portions extending from the lateral ends around the dial through the 75 central opening therein, the ends of the hands being in front of the dial and overlying time markings thereon, the hands being slightly spaced from each other and the casing and dial, and defining a recess behind the dial substantially as large as the casing, and a changeable exhibitor apparatus mounted in said recess behind the dial for displaying advertising matter through the opening therein, said apparatus having 80 85 portions concealed from view by the dial.

In testimony whereof I affix my signature in presence of two witnesses.

MAX SCHMIDT.

Witnesses:

WALTER TUCHENY,
ULRICH MULLER.
